UNITED STATES PATENT OFFICE.

JOHN E. WOOTTEN, OF PHILADELPHIA, PENNSYLVANIA, ASSIGNOR TO THE WHARTON RAILROAD SWITCH COMPANY, OF SAME PLACE.

LOCOMOTIVE-BOILER.

SPECIFICATION forming part of Letters Patent No. 352,215, dated November 9, 1886.

Application filed August 30, 1886. Serial No. 212,148. (No model.)

To all whom it may concern:

Be it known that I, JOHN E. WOOTTEN, of the city and county of Philadelphia, in the State of Pennsylvania, have invented certain new and useful Improvements in Locomotive-Boilers, of which improvements the following is a specification.

My improvements more particularly relate to locomotive-boilers of the wide fire-box type, instances of which are illustrated in my Letters Patent No. 192,725, July 3, 1877; No. 254,581, March 7, 1882, and No. 291,120, January 1, 1884; and its object is to enable the advantages of such type, in affording a largely increased grate-area without undue elevation of the center of gravity of the boiler, to be realized without necessarily providing a combustion-chamber within the waist of the boiler.

To this end my invention, generally stated, consists in the combination, with a locomotive-boiler having a fire-box extended laterally beyond its shell, of a fire-bridge located wholly within the fire-box and supported above the grate thereof in such relation to the tube-sheet as to form a space or chamber in the rear thereof, which is closed at its bottom and open at its top for the free passage of the products of combustion from the fire-box to the tubes.

The improvements claimed are hereinafter fully set forth.

In the accompanying drawings, Figure 1 is a vertical longitudinal central section through a locomotive-boiler embodying my invention; Fig. 2, a horizontal section through the fire-box thereof at the line *a b* of Fig. 3; Fig. 3, a transverse section through the same at the line *c d* of Fig. 1; Fig. 4, a vertical longitudinal central section through a locomotive-boiler, illustrating a modification of my invention; Fig. 5, a horizontal section through the fire-box thereof at the line *e f* of Fig. 6; Fig. 6, a transverse section through the same at the line *g h* of Fig. 4; Fig. 7, a vertical longitudinal central section through a locomotive-boiler, illustrating another modification of my invention; Fig. 8, a horizontal section through the fire-box thereof at the line *i k* of Fig. 9; Fig. 9, a transverse section at the line *l m* of

Fig. 7; Fig. 10, a vertical longitudinal central section through a locomotive-boiler, illustrating a further modification of my invention; Fig. 11, a horizontal section through the fire-box thereof at the line *n o* of Fig. 12, and Fig. 12 a transverse section through the same at the line *p q* of Fig. 10.

The several modifications of my invention herein described, each of which embodies in a form adapted to practical operation its essential features, are illustrated as applied in a locomotive-boiler having its cylindrical waist or barrel 1 fitted with a series of fire-tubes, 2, which extend in the ordinary manner from the smoke-box 3 to the fire-box 4. The fire-box is so located relatively to the waist as to be entirely above the driving-wheels of the engine, and its bottom may be either, as shown, substantially in the same horizontal plane as the bottom line of the waist, or be entirely above the same, as preferred. It is likewise extended laterally beyond the waist and the planes of the driving-wheels to any desired extent within the maximum width admissible for passage over the road, as in previous constructions of the wide fire-box type.

In boilers of this type as heretofore constructed provision for the prevention of the passage of unconsumed fuel into the tubes has consisted in a fire-bridge extending across the rear of a combustion-chamber formed within the waist at the end thereof adjacent to the fire-box. Under my present invention said combustion-chamber and fire-bridge in the waist are dispensed with, the tubes being made of correspondingly-greater length, and extending, as in the ordinary locomotive-boiler, to the tube-sheet 5. In order to enable a fire of proper thickness to be carried upon the grate 6 without involving liability of the ingress of fuel to the tubes by being thrown thereinto in firing or drawn or jolted thereinto from the grate, as well as to afford a free space within the fire-box for perfecting the combustion of the gases before their passage into the tubes, I provide a fire-bridge, 7, composed, preferably, of fire-brick, as shown, but which may, if preferred, be in the form of a water wall or chamber communicating at its ends with a water space or spaces of the

fire-box, said fire-bridge being located entirely within the fire-box, above the grate 6, and at such distance in rear of the tube-sheet 5 and above the top of the grate as will institute between its front side and the tube-sheet 5 a combustion space or chamber, 8, of sufficient volume to admit of the free passage of the gases evolved from the burning fuel, which rests upon that portion of the grate 6 in rear of the fire-bridge, to the tubes 2.

The fire-bridge 7 rests upon and is supported by a plate, 9, which extends from its front side to the tube-sheet 5 upon or closely adjacent to the top line of the grate 6, and closes at bottom the space 8 in front of the fire-bridge, thereby preventing the passage of cold air from the ash-pan into the tubes, and making the space between the crown-sheet 10 and the top of the fire-bridge the only avenue of communication between the rear portion of the fire-box, in which the fuel is contained, and the tubes. The supporting-plate 9 is held in position by suitable lugs or bearers, 11, secured to the fire-box sheets. The ends of the fire-bridge abut against the inside of the fire-box, their distance apart being either equal to the entire inside width of the fire-box, or to a distance less than said inside width and greater than the diameter of the waist, so that in all cases the fire-bridge shall be completely interposed between the rear ends of the tubes and the portion of the grate in the rear of the fire-bridge on which the fuel is carried in the operation of the boiler, so as to serve throughout its entire extent as a barrier to the passage of fuel into the tubes.

It will be obvious that while my invention enables a combustion-chamber within the waist of the boiler to be dispensed with, such a chamber may, if deemed advisable, be employed, and my improvements are equally adaptable to locomotive-boilers provided with the same.

The specific form and position of the fire-bridge may be varied in many particulars without departing from the spirit and principle of operation of my invention, and modifications thereof in such particulars are shown in the drawings. Thus, as illustrated in Figs. 1 to 3, the fire-bridge, which is vertical and is rectangular both in vertical and in horizontal section, extends completely across the fire-box, abutting at its ends against the side walls thereof and providing a combustion-space of the full width of the fire-box. As shown in the remaining figures, the fire-bridge is curved or segmental in horizontal section, each of its ends fitting against the tube-sheet 5 at a distance apart greater than the diameter of the waist. A fire-bridge having a central portion parallel to the tube-sheet, and two inclined sides extending thereto from the central portion, would be an equivalent construction.

The fire-bridge of Figs. 4 to 6 is vertical, and those of Figs. 7 to 9 and 10 to 12 are in each case rearwardly inclined from their lower

to their upper surfaces, thereby increasing the volume of the combustion-space 8 relatively to that afforded by a vertical fire-bridge.

The fire-bridge of Figs. 10 to 12 further differs from the others illustrated in the particular of abutting at its bottom against the tube-sheet, which construction may be adopted where a minimum reduction of great area is considered desirable.

Suitable means may be provided for the injection of currents of heated air, or of air and steam, into the combustion-space 8 for the purpose of promoting and perfecting combustion and the prevention of smoke; but the same do not constitute part of my present invention, and, so far as they may embody novel and patentable features, will form the subject of a subsequent application or applications.

My invention, while retaining to a substantial degree the advantageous features of wide fire-box boilers of the construction which has been heretofore approved in practical service, affords the advantages of a reduction in cost and an increased amount of area of tube-heating surface relatively thereto. The fire-bridge can be readily applied and fitted in position and is conveniently accessible for renewal and repair, and the grate-area attainable in boilers of this type is so ample that no objection results from such curtailment thereof as is involved in locating the fire-bridge and combustion-space within the fire-box and above a portion of the grate.

I claim as my invention and desire to secure by Letters Patent—

1. The combination, in a locomotive-boiler, of a laterally-extended fire-box having a grate at or near the lower line of the waist of the boiler, and a fire-bridge located wholly within the fire-box and above the grate and extending upwardly from the plane of the grate in rear of and out of contact with the tube-sheet, substantially as set forth.

2. The combination, in a locomotive-boiler, of a laterally-extended fire-box having a grate at or near the lower line of the waist of the boiler, and a fire-bridge located wholly within the fire-box and above the grate, and extending upwardly from the plane of the grate, said fire-bridge forming the rearward boundary of a combustion space or chamber adjacent to the tube-sheet, which space is closed at bottom and open at top for the free passage of gases to the tubes, substantially as set forth.

3. The combination, in a locomotive-boiler, of a laterally-extended fire-box, and a fire-bridge located wholly therein at and above the grate-level, and of greater width than the diameter of the waist of the boiler, substantially as set forth.

4. The combination, in a locomotive-boiler, of a laterally-extended fire-box, a supporting-plate located therein at or near the level of the grate, and a fire-bridge resting upon said supporting-plate and interposed throughout its entire extent between the tube-sheet and the

portion of the grate not covered by the supporting-plate, substantially as set forth.

5. The combination, in a locomotive-boiler, of a laterally-extended fire-box, and a fire-bridge located wholly therein at and above the grate-level and forming the rearward boundary of a combustion space or chamber adjacent to

the tube-sheet, said fire-bridge being rearwardly inclined from its lower to its upper surface, substantially as set forth.

JOHN E. WOOTTON.
